Attest,

UNITED STATES PATENT OFFICE.

HAROLD J. BELL, OF GLOUCESTER, NEW JERSEY, ASSIGNOR TO THE WELS-BACH INCANDESCENT GAS LIGHT COMPANY, OF NEW JERSEY.

ATMOSPHERIC GAS-BURNER.

SPECIFICATION forming part of Letters Patent No. 396,256, dated January 15, 1889.

Application filed May 10, 1888. Serial No. 273,457. (No model.)

To all whom it may concern:

Be it known that I, HAROLD J. BELL, a citizen of the United States, residing at Gloucester, in the county of Camden and State of New Jersey, have invented new and useful Improvements in Atmospheric Gas-Burners, of which the following is a specification.

This invention relates to atmospheric gas-burners for incandescent illumination; and it consists in the construction and combination of parts, as hereinafter set forth.

The invention is illustrated in the annexed drawings, in which—

Figure 1 is a vertical section of a burner, atmospheric gas-tube, and vertically-adjustable shield, showing the shield and burner-tube as partially closing the lateral air-inlets of the atmospheric gas-tube. Fig. 2 is an elevation of the atmospheric gas-tube and vertically-adjustable shield, the burner being detached.

The atmospheric gas-tube 1 is provided with the usual lateral air-inlets, 2, and beneath these air-openings it may have a horizontal finely-perforated disk or diaphragm, 3, to divide the supply of gas into fine currents, whereby an intimate mixture of gas and air can be produced in the tube. The lower end of the tube 1, beneath the perforated disk 3, is internally threaded to engage a gas-fixture.

As shown, the base of the atmospheric gas-tube 1, beneath the air-inlets 2, is externally screw-threaded, to engage a spiral ring, 4, that is supported concentrically within a bell-shaped shield, 5, which by rotation in the proper direction is thus made vertically-adjustable, upward or downward, as required, on the gas-tube.

The vertically-adjustable shield 5 serves to prevent the disturbing influences of external air-currents, and also affords an adjustable support for the burner-tube 6, the lower end of which serves to close the air-inlets 2 more or less when the shield 5 is lowered.

The burner-tube 6 may be of any suitable construction. As shown, it is provided at the top with a gas and air mixing chamber, 7, enclosing a gauze diaphragm, 8, above which is seated a burner-tip, 9, having a circular series

of gas-exits, 10, opening into an annular flame-passage, 11, the construction of these parts being similar to that shown in an application, Serial No. 266,505, filed by me March 8, 1888. If desired, the burner-tip and upper part 55 of the tube 6 may be surrounded at a suitable distance by a deep annular deflector, 12, which forms, with the outer wall of the burner-tip, an annular chamber to receive and conceal the lower ragged edge or skirt of a Welsbach mantle. This deflector is attached to the burner-tube 6, and may support a chimney-gallery, as described and shown in an application filed by me May 10, 1888, Serial No. 273,456. 65

In order to regulate the draft and increase or diminish the quantity of air admitted through the lateral air-inlets 2, as may be required, it is only necessary to rotate the bell-shaped shield 5, thereby raising or lowering 70 said shield, together with the burner-tube 6 and attached parts. By lowering the shield 5 the lower end of the burner-tube 6 will be made to partially or wholly cover the air-inlets 2, according to the amount of movement 75 given to said shield and tube; and I am thus enabled to dispense with a neck on the shield, as employed in the construction illustrated in an application filed by me May 10, 1888, Serial No. 273,455. By dispensing with a 80 neck on the shield 5 and employing the lower end of the movable burner-tube 6 to control the air-inlets, the length of the tubes can be shortened considerably.

When the shield 5 and burner-tube 6 are 85 raised to partially or wholly uncover the lateral air-inlets 2, the depending portion of the shield surrounding said air-inlets at a distance therefrom will still serve to break the force of external air-currents and maintain a steady 90 draft. When the shield 5 is lowered sufficiently to permit the burner-tube 6 to descend far enough to wholly close the air-inlets 2, access of air will of course be entirely cut off. With this simple construction, therefore, the 95 quantity of air admitted to the burner can be readily controlled at will.

I would have it understood that I do not herein claim the particular form of burner-tip shown and described, as such is claimed in an 100

application, Serial No. 266,505, filed by me March 8, 1888; nor do I claim a combined burner and gallery, as such is claimed in an application, Serial No. 273,456, filed by me May 5 10, 1888.

What I claim is—

1. The combination, with an atmospheric gas-tube having lateral air-inlets, of a vertically-adjustable bell-shaped shield movably supported on the base of said tube and a vertically-adjustable burner-tube supported on the shield and movable therewith to cover and uncover the lateral air-inlets, substantially as described.

2. The combination of an atmospheric gas-tube having lateral air-inlets and an externally-screw-threaded base, a vertically-adjustable bell-shaped shield having an internal spiral ring to engage the said externally-screw-threaded base, and a vertically-adjustable burner-tube supported on the shield and movable therewith, substantially as described.

In testimony whereof I affix my signature in presence of two witnesses.

HAROLD J. BELL.
